UNITED STATES PATENT OFFICE.

JAMES FRANK TENNEY AND CHARLES F. CRANZ, OF CHICAGO, ILLINOIS.

DESIGN FOR A FONT OF TYPE.

SPECIFICATION forming part of Design No. 34,053, dated February 5, 1901.

Application filed April 14, 1900. Serial No. 12,942. Term of patent 3½ years.

To all whom it may concern:

Be it known that we, JAMES FRANK TENNEY and CHARLES F. CRANZ, citizens of the United States, residing at Chicago, in the county of Cook and State of Illinois, have invented and produced a novel Design for a Font of Type; and we do hereby declare the following to be a full, clear, and exact description of the invention.

Our invention relates to a novel design for a font of printing-type, the object being to provide a set of characters of graceful and highly-ornamental form; and it consists in the novel features hereinafter described and claimed.

The accompanying drawing, illustrating our design, shows a full set of characters forming a font of type.

The peculiarities of the design are that each line or curve of each character terminates in a circular enlargement at one end, producing the appearance that such lines and curves terminate in balls or globes. The horizontals of most of the characters form ogee curves. The half-ovals of letters such as B, D, P, R, ²⁵ S and Q are exaggerated. The capital letters C, O, and Q and small letters e, o, and r have each a dot to fill out the space. The type are all solid face, the letters being of lighter face than the figures, and the punctuation-marks and miscellaneous characters—such as &, $, ¢, &c.—smaller than the letters. The capital letters I, K, M, V, W, X, Y, and Z and the small letters i, j, k, l, v, w, x, y, and z are made up of straight lines only. ³⁰ ³⁵

We claim as our invention—

The design for a font of type, substantially as shown and described.

In testimony whereof we affix our signatures in presence of two witnesses.

J. FRANK TENNEY.
CHARLES F. CRANZ.
